Inventor:

UNITED STATES PATENT OFFICE.

IRVING C. WOODWARD, OF CHICAGO, ILLINOIS.

NUT-LOCK.

1,000,657.

Specification of Letters Patent. Patented Aug. 15, 1911.

Application filed October 21, 1910. Serial No. 588,293.

To all whom it may concern:

Be it known that I, IRVING C. WOODWARD, a citizen of the United States of America, and a resident of Chicago, county of Cook, State of Illinois, have invented certain new and useful Improvements in Nut-Locks, of which the following is a specification.

The main objects of this invention are to provide a simple, efficient, and inexpensive form of nut lock:

An illustrative embodiment of this invention is shown in the accompanying drawings, in which—

Figure 1 shows a nut and bolt locked by a nut lock constructed according to this invention. Fig. 2 is a section of the same taken on the line A—A of Fig. 1. Fig. 3 is a plan view of the blank before being bent. Fig. 4 is a front elevation of the finished nut lock showing the eccentricity of the apertures. Fig. 5 is a section of the same taken on the line B—B of Fig. 4.

In the form shown in the drawings the nut lock comprises a flat piece of resilient metal 1 bent upon itself to substantially U shape so as to form a pair of legs 2 and 3 extending in the same general direction and connected together by an inclined back or yoke 4. Apertures 5 and 6 are punched in the blank so that, when the piece of metal is bent to the shape shown in the drawings, they will be eccentrically located with respect to each other and their centers will lie in a line inclined to the legs in the same general direction as the inclination of the back. These apertures are unthreaded and are preferably oblong or elliptical, the major mean between the outside and root diameters being greater than the outside diameter of the bolt.

The size of the apertures 5 and 6 and their relative location allows the edge of each aperture to be seated in the thread grooves 7 for a short distance only as at 8 and 9 respectively. On account of the eccentricity of the apertures the legs of the lock engage respectively opposite sides of the bolt. When in position on the bolt the adjacent leg 2 of the lock comes up flush against the face of the nut 10 and the back 4 is inclined away from the bolt and from the face of the nut.

The nut lock may be screwed on with the fingers up to the nut 10 and then it may be set up with a wrench thereby wedging the edge of the aperture at 5 between the thread

and the face of the nut 10. For all ordinary uses the "setting up" of the nut lock with the wrench will, on account of the incidental springing together of the legs of the lock, secure the nut 10 against removal until the nut lock has first been removed. However, it may in some instances as with small bolts where the resiliency of the nut lock is reduced to a minimum due to its size, be desirable to cause a more secure seating of the parts 8 and 9 in the thread grooves 7. This can be accomplished by striking a blow with a hammer at 8 which, on account of the inclination of the back, will tend to increase the eccentricity of the apertures and thereby increase the grip of the nut lock on the bolt.

Although but one specific embodiment of this invention has been herein shown, it will be understood that numerous details of the construction shown may be altered or omitted without departing from the spirit of this invention.

I claim:

1. A nut lock, comprising a piece of metal bent upon itself to form a pair of legs extending in the same general direction and having eccentrically located apertures therein.

2. A nut lock, comprising a flat piece of metal bent upon itself to form a pair of legs extending in the same general direction, each of said legs having an aperture therein, said apertures being eccentrically located relatively to each other.

3. A nut lock, comprising a flat piece of metal bent upon itself to form a pair of legs extending in the same general direction, each of said legs having an aperture therein, said apertures being oblong and eccentrically located relatively of each other.

4. A nut lock comprising a flat piece of metal bent upon itself to form a pair of legs extending in the same general direction, each of said legs having an aperture therein, said apertures being oblong and eccentrically located relatively of each other in the direction of their shorter diameters.

5. A nut lock, comprising a flat piece of metal, having therein a pair of apertures spaced apart and being bent upon itself between said apertures to form a pair of legs extending in the same general direction and connected by a back inclined at an angle to said general direction, the inclination of said back being such as to make the apertures in said legs eccentric to each other.

6. A nut lock, comprising a piece of metal having therein a pair of apertures spaced apart and being bent upon itself to form a pair of legs extending in the same general direction and having eccentrically located apertures therein, and a back inclined at an acute angle to one of said legs.
7. A nut lock, comprising a piece of metal bent upon itself to form a pair of legs extending in the same general direction and having eccentrically located apertures therein, and a back connecting said legs and inclined thereto in the general direction of the line of centers of said eccentric apertures.
8. The combination with a bolt and nut, of a nut lock comprising a flat piece of metal bent upon itself to form a pair of legs extending in the same general direction, each of said legs having an aperture therein, the edge of one of said apertures being adapted to engage the threads of the bolt at a point circumferentially spaced away from the point of engagement of the edge of said other aperture with said threads.
9. The combination with a bolt and nut, of a nut lock comprising a flat piece of metal bent upon itself to form a pair of legs extending in the same general direction, each of said legs having an aperture therein, the edge of one of said apertures being adapted to engage the threads of the bolt at a point substantially diametrically opposite to the point of engagement of the edge of said other aperture with said threads.
10. The combination with a bolt and nut, of a nut lock comprising a flat piece of metal bent upon itself to form a pair of legs extending in the same general direction,
- each of said legs having an unthreaded aperture therein, the edge of one of said apertures being adapted to engage the threads of the bolt at a point circumferentially spaced away from the point of engagement of the edge of said other aperture with said threads.
11. The combination with a bolt and nut, of a nut lock comprising a flat piece of metal bent upon itself to form a pair of legs extending in the same general direction, each of said legs having an aperture therein, said apertures being of a diameter not less than the mean between the outside and root diameters of the bolt, the edges of said apertures being adapted to be seated in the thread grooves at points spaced apart circumferentially.
12. The combination with a nut and bolt of a nut lock comprising a flat piece of metal bent upon itself to form a pair of legs extending in the same general direction, each of said legs having an oblong aperture therein, the major diameter of said aperture being not less than the outside diameter of said bolt, and the minor diameter being not less than the mean between the outside and root diameters of said bolt, the edges of said apertures being adapted to become seated in the thread grooves at points substantially diametrically opposite.

Correction in Letters Patent No. 1,000,657.

It is hereby certified that in Letters Patent No. 1,000,657, granted August 15, 1911, upon the application of Irving C. Woodward, of Chicago, Illinois, for an improvement in "Nut-Locks," an error appears in the printed specification requiring correction as follows: Page 1, lines 36-40 the sentence "These apertures are unthreaded and are preferably oblong or elliptical, the major mean between the outside and root diameters being greater than the outside diameter of the bolt." should read *These apertures are unthreaded and are preferably oblong or elliptical, the major diameter being greater than the outside diameter of the bolt, and the minor diameter not less than the mean between the outside and root diameters of the bolt.*; and that the said Letters Patent should be read with this correction therein that the same may conform to the record of the case in the Patent Office.

Signed and sealed this 3rd day of October, A. D., 1911.

Commissioner of Patents.

6. A nut lock, comprising a piece of metal having therein a pair of apertures spaced apart and being bent upon itself to form a pair of legs extending in the same general direction and having eccentrically located apertures therein, and a back inclined at an acute angle to one of said legs.
7. A nut lock, comprising a piece of metal bent upon itself to form a pair of legs extending in the same general direction and having eccentrically located apertures therein, and a back connecting said legs and inclined thereto in the general direction of the line of centers of said eccentric apertures.
8. The combination with a bolt and nut, of a nut lock comprising a flat piece of metal bent upon itself to form a pair of legs extending in the same general direction, each of said legs having an aperture therein, the edge of one of said apertures being adapted to engage the threads of the bolt at a point circumferentially spaced away from the point of engagement of the edge of said other aperture with said threads.
9. The combination with a bolt and nut, of a nut lock comprising a flat piece of metal bent upon itself to form a pair of legs extending in the same general direction, each of said legs having an aperture therein, the edge of one of said apertures being adapted to engage the threads of the bolt at a point substantially diametrically opposite to the point of engagement of the edge of said other aperture with said threads.
10. The combination with a bolt and nut, of a nut lock comprising a flat piece of metal bent upon itself to form a pair of legs extending in the same general direction,
- each of said legs having an unthreaded aperture therein, the edge of one of said apertures being adapted to engage the threads of the bolt at a point circumferentially spaced away from the point of engagement of the edge of said other aperture with said threads.
11. The combination with a bolt and nut, of a nut lock comprising a flat piece of metal bent upon itself to form a pair of legs extending in the same general direction, each of said legs having an aperture therein, said apertures being of a diameter not less than the mean between the outside and root diameters of the bolt, the edges of said apertures being adapted to be seated in the thread grooves at points spaced apart circumferentially.
12. The combination with a nut and bolt of a nut lock comprising a flat piece of metal bent upon itself to form a pair of legs extending in the same general direction, each of said legs having an oblong aperture therein, the major diameter of said aperture being not less than the outside diameter of said bolt, and the minor diameter being not less than the mean between the outside and root diameters of said bolt, the edges of said apertures being adapted to become seated in the thread grooves at points substantially diametrically opposite.
